METHOD AND APPARATUS FOR WELL DRILLING AND TESTING

Donovan B. Grable, Long Beach, Calif.

Application February 16, 1952, Serial No. 271,927

15 Claims. (Cl. 255—1.4)

1

This invention has to do with improved systems for drilling, testing and producing oil wells, and is directed particularly to novel methods and apparatus characterized by the employment of a dual pipe or drill string made up of an inner pipe section contained within and spaced from an outer pipe section so that drilling circulation or other fluid flow may be maintained downwardly within one of the pipe passages and upwardly within the other pipe passage to the ground surface through the other pipe passages. Well drilling systems employing such composite pipe strings are also dealt with in my copending applications Serial No. 139,655, filed January 20, 1950, on Method and Apparatus for Drilling Wells, and Serial No. 243,626, filed August 25, 1951, on Method and Apparatus Employing Compressed Gas for Drilling Wells.

One of the primary advantages in the use of the dual pipe string as a fluid conductor, is that it permits the maintenance of fluid circulation, as to and from a drill bit, while isolating the well bore above the working vicinity of the bit from contact with the circulated mud. As a result, the wall of the hole is left as nearly as possible in a natural uncaked condition free from restrictions and washouts ordinarily caused by mud deposits and continued circulation fluid flow. Similarly, the composition of the formation at any given location, including at the bit, remains relatively free from contamination by materials normally distributed throughout the exposed surface of the formation by conventional mud or drilling fluid circulation which flows in contact with and throughout the extent of the well bore.

The present invention is concerned in one of its major aspects with well testing and fluid displacement from the well, by new methods and equipment benefiting also as to accomplishment of their objectives, from confinement to the dual pipe string of fluid flow into and out of the well. Specifically contemplated are situations of pressurized circulation or fluid displacement (1) into and out of a lower or bottom zone of the well, and (2) through an upper extent of the drill string assembly, while the lower portion of the string is packed off from the formation, this positively isolating the circulation and imposed pressure effects from the formation above the packer.

As illustrative of a typical operation contemplated by the invention, its objective may be to test the formation or fluid composition or flow rates into a bottom section of the well bore. Preparatory to sample taking or flow movement, the formation is packed off at a location prefer-

2

ably near the bottom of the hole by a fluid pressure expansible packer carried by the string and communicable with the pipe string, and preferably the inner pipe for expansion by fluid pressure therein. Above the packer the inner pipe contains vertically spaced ports through which a lifting fluid may flow from one into the other of the pipe section passages, and ordinarily in downward sequence to progressively displace to the ground surface liquid standing in or entering the string from the well below the packer. Preferably the ports normally are closed by individual valves which may be selectively opened as in downward sequence, to admit the lifting fluid, preferably air or other gas, to the discharge passage. Typically, and preferably, compressed air is delivered to the inter-pipe space for discharge through the sequentially opened ports into the inner pipe which is in communication with the zone to be tested. As a result of the progressive displacement of liquid from the inner pipe, it is possible to remove from above the test zone substantially all liquid initially present, and thereafter to displace from the test zone true samples of the materials therein, or of the fluids directly entering the zone from the formation, uncontaminated with liquids or solids from other sources.

As will appear, the invention presents the important accomplishment of providing a drill string and appurtenant equipment, useable for either or both drilling and testing apparatus. Following a period of drilling to the depth of a particular formation to be investigated, the string and associated parts may be converted to testing purposes, after which the equipment may be restored to drilling conditions, all without having to pull the string or undertake other than simple operations.

All the various features and objects of the invention, as well as the details of certain typical embodiments, will be more fully understood from the following detailed description of the structure and operation of the illustrative equipment shown by the accompanying drawings, in which:

Fig. 1 is a general view showing the apparatus positioned for operation in a well;

Fig. 2 is a sectional enlargement of the goose-neck swivel head;

Fig. 3 is a fragmentary enlargement of the bottom portion of the drill string showing the packer and the bit below;

Fig. 4 is a fragmentary enlarged cross section taken on line 4—4 of Fig. 1 through one of the sleeve valves;

Fig. 5 illustrates the valve of Fig. 4 in open position, and Fig. 6 is a cross section on line 6—6 of Fig. 1.

Referring first to the general showing of Fig. 1, the dual section pipe string 10 is shown to be lowered in the well bore 11 and to include an upper Kelly stand 12 extending through the casting head 13 and rotary table 14 which operates in the usual manner to rotate the string 10. The head 13 has appropriate pipe connections 15 and 16 for the introduction or escape of liquid or gaseous fluids from the well bore at the outside of the pipe string. The latter is vertically supported by the swivel head 17 having the usual type of bale 18 to be hooked to the traveling block, not shown.

Referring to Figs. 3 and 4, the pipe string 10 comprises an outer pipe 19 and an inner pipe 20, the pipes being annularly spaced to provide a flow passage 21 which preferably corresponds in cross sectional area to the bore or flow passage 22 in the inner pipe. The stands of the respective pipes are interconnected by threaded internally flush, externally upset joints 23 and 24, and beyond the joints the stands are interconnected by circularly spaced welded inserts 25. The structural details of the dual pipe string, their method of interconnection and the advantages of particular types of threaded joints, are more specifically dealt with in my copending applications referred to hereinabove. At its lower end the pipe string carries a suitable form of drill bit 26 having a passage 27 communicating with the pipe string passage 21 and communicating through passages 28 and 29 with the inner pipe bore 30. Thus fluid circulation may be maintained through the bit passages 27, 28 and 29 from the pipe string passage 21 into passage 30, or reversely from passage 30 into the outer passage 21.

For more detailed description of the swivel head assembly illustrated in Fig. 2, reference may be had to my first filed application Serial No. 139,-655. For present purposes it will suffice to describe the assembly 17 as comprising a tubular body 31 containing a stem 32 rotatable within bearing 33 and connected at 34 to the Kelly 12. At its upper end the stem 32 is rotatable within its packed joint at 35 with gooseneck 36 connected to the hose 37. The upper belled end 20a of the inner pipe 20 receives and is rotatable at 33a within the lower end of a second gooseneck 36a connected to the hose 37a. The gooseneck 36 has an axially alined branch 38 which normally is plugged, but upon removal of the plug receives a flexible line passing attachment 39. The latter may be in the nature of a lubricator comprising a tubular body 40 threaded into the branch 38 and containing a rubber packer or wiper adapted to seal about the wire line 42 which may be run into the pipe string as later described. As will be understood, the gooseneck 36 communicates through passage 43 with the interpipe passages 21, and gooseneck 36a communicates through its bore 44 with the passage 30 in the inner pipe 20.

The pipe string 10 carries at its lower end, and preferably at a location just above the bit 26, a fluid pressure expansible packer generally indicated at 46. This packer may be of any of various known types adapted to be expanded in response to internally applied pressure, into engagement with the wall of the well bore 11. Merely as illustrative, the packer is shown to comprise a rubber sleeve 47 having clamped confine-

ment at its upper and lower ends about the outer pipe 19 within fittings 48 which in turn are clamped rigidly to the pipe. Fluid pressure is communicable to the interior 49 of the packer from the pipe string, and preferably from within the inner pipe 20 through one or more tubular valve bodies 50 terminating within the inner and outer pipes and containing a ball check 51 normally held by coil spring 52 against its seat 53. Below the check valve, the inner pipe 20 contains a seat 54 having an opening 55 adapted to be closed temporarily by a ball check 56 which is dropped down into place within the pipe string.

Above the packer 46 the inner pipe 20 carries at suitable intervals, say in the order of 200 feet spacing, a series of selectively openable valves generally indicated at 57, see Figs. 4 and 5, which may be of any appropriate type adapted to establish temporary communication between the pipe string passages 21 and 22 at the location of the valves. Typically each valve assembly 57 is shown to comprise a tubular vertically movable sleeve valve 58 adapted to seat downwardly against shoulder 59 and containing ports 60 movable into and out of registration with port 61. Upward displacement of the valve from its normal position of seating against shoulder 59 (in which passages 60 and 61 are in effect closed) is resisted by coil spring 62 confined between the top of the valve and the pipe shoulder 63.

Each valve may be selectively opened by a suitable tool, such as I have illustrated at 64, run down in the pipe string through the lubricator 39 on the wire line 42. The tool 64 typically is shown to comprise a yoke 65 connected at 66 to the wire line and carrying a pair of grapple dogs 67 pivoted at 68 on the yoke and so mounted as to tend to lie outwardly against the pipe. When lowered to the Fig. 5 position, the dogs 67 are receivable within the sleeve recess 69 and engageable against shoulder 70 so that an upward pull on the wire line raises the valve. Dogs 67 are releasable from engagement with the shoulder by tubular go-devil 71 which may be dropped down on the wire line to engage the inner ends 69a of the dogs and thus swing the latter inwardly away from the shoulder 70.

In considering the operation and methods of using the equipment, assume first that normal drilling operations are in progress with the packer 46 deflated and the drill string rotated by the drive transmitted to the kelly from the rotary table 14. A suitable circulating fluid such as an oil or water base mud, or a gaseous fluid such as air, is discharged from hose 37 through passages 43 and 21 to the drill bit 26 wherein the fluid flows inwardly from passage 27 through passage 28 into the bit bore 29, entraining the cuttings as they are severed from the formation by the bit, for removal in the fluid stream rising through the inner pipe 20 and discharging through the gooseneck 36 to hose 37. During such circulation a liquid column may be maintained in the well bore 11 outside the drill string at a level sufficiently high to impose at the bit a hydrostatic pressure, such as to require the circulation through the drill string passages to be confined substantially entirely to flow within the bit, i. e., through passages 28. The function of the well liquid column thus is primarily to maintain an essentially static column of fluid some of which progressively feeds into the bit to be induced along with the cuttings and circulation fluid, into the discharge stream going to the

5

ground surface. Any liquid make up to the well liquid column may be supplied through line 15, and by the use of an appropriate back pressure valve V in line 16, any desired pressure may be maintained within the well.

Assume next that drilling has progressed into a formation or sand requiring test or identification to determine its composition or relation to other structures in the formation. The invention now affords a means of obtaining a true and uncontaminated sample of the sand or other formation at the particular depth of the bit. First the packer 46 is expanded by dropping the ball check 56 onto its seat 54 and pumping or compressing fluid down within the inner pipe 20 at a pressure sufficient to unseat the check valve 51 and discharge the fluid into the interior 49 of the packer sleeve 47. Upon expansion of the packer into the Fig. 3 broken line condition 47a of engagement with the well bore wall, the fluid pressure transmission is discontinued and valves 51 seat to maintain the expanding condition of the fluid inside the packer. Fluid circulation then may be conducted downwardly through passage 21 and up through the inner pipe bore 30 to displace the ball check 56 out through the gooseneck 36.

The valves 57 then may be operated in downward sequence to introduce air or other gas into the inner pipe for the purpose of progressively displacing all liquid standing in the inner pipe above the lowermost valve, while simultaneously displacing any liquid well inflow above that location, which may occur during the operation. By lowering the tool 64 on wire line 42 into the uppermost valve 57, the latter may be lifted to bring ports 60 and 61 into registration and permit flow from passage 21 into the inner pipe passage of compressed air being discharged into the string from hose 31. The air flow is maintained until the liquid within the inner pipe above the valve is displaced out through hose 31. Thereafter, the tool 64 is lowered to open the valve next below, whereupon the air circulation is maintained to displace to the ground surface the liquid above the valve, and so on as the valves are successively open in downward sequence, and successive segments of the liquid column are displaced out of the inner pipe. With the lowermost valve positioned just above the packer 46, it is thus possible to remove from the pipe string substantially all liquid and the sands and cuttings entrained therein. By dropping the go-devil 71, the dogs 67 may be collapsed to permit the tool to be withdrawn from the string.

A suitable fluid, preferably a gas such as air, now is circulated down through passage 21 and the bit passages to displace sand or other loose formation material from within the bit up through the inner pipe for recovery from the gooseneck 36. As will be appreciated, the sample thus obtained is virtually uncontaminated and represents the true composition of the sampled material as it exists at the location of the bit. Following the sample operation the packer may be deflated for continuance of drilling operations or for any other purpose, by lowering within the inner pipe a weighted tool 70, see Fig. 3, capable of engaging and unseating the check valves 51 to relieve the fluid pressure from within the packer and thereby enable the latter to restore to deflated condition.

The invention further contemplates the testing of bottom hole conditions by appropriate instrumentation run down through the inner pipe section after sealing about the drill string by ex-

6

pansion of the packer as previously described, and either before or after displacement of the well fluid from the pipe string by the described sequential operation of the air valves. Referring to Fig. 3, I have indicated at I an instrument which may be run down on a wire line through the inner section of the string to the bottom of the hole after expansion of the packer, and for example after displacement of the liquid from the inner pipe and following removal of the tool 64 and ball check 56. The instrument I may be of any of the appropriate known types for indicating or recording bottom hole pressures, and as will be apparent, with the packer expanded to seal off against the formation above, the pressure recorded or indicated by the instrument affords a true determination of the actual bottom hole pressure, independently of any fluid column pressure outside the drill string and above the packer.

The instrument indicated at I may instead be regarded as a diagrammatic showing of an electrical logging instrument which may be operated under similar conditions for electrically surveying the bore wall formation at any location below the packer. Regarding the instrument I as any known or appropriate type of electrical logging instrument, the survey may be made with the instrument position as shown, or the pipe string may be raised and the instrument run out through the bit into the open hole. As will be understood from the foregoing, with the formation and any fluid column sealed off by and above the packer, and particularly after removal of any liquids from the pipe string which for any reason might adversely affect the survey, the electrical logging operation may be conducted in the sealed-off bottom of the hole free from any interference which ordinarily might be encountered in the absence of the seal off.

I claim:

1. Oil well equipment comprising a pipe string including an inner pipe and an outer pipe spaced therefrom, an expandable packer carried by said outer pipe near the lower end thereof and adapted to be expanded against the well bore wall, means for expanding said packer, said pipes being in communication with each other and with the well at a location beneath said packer, a port in said inner pipe providing communication between said inner and outer pipes at a location spaced above said first-mentioned location, a valve controlling fluid flow through said port, and means for actuating said valve.

2. Oil well equipment as recited in claim 1, including a plurality of said ports in the inner pipe at a plurality of vertically spaced locations above said first location, valves controlling fluid flow through said ports, and means for individually and selectively controlling said valves.

3. Oil well equipment as recited in claim 1, including a drilling tool carried by the lower end of said string and containing passages through which said inner and outer pipes are in communication with each other and with the well.

4. Oil well equipment as recited in claim 1 in which said packer is adapted for expansion outwardly by fluid pressure communicated thereto from within the string.

5. Oil well equipment as recited in claim 1 in which said packer is adapted for expansion outwardly by fluid pressure, and including passage means for communicating fluid pressure from said inner pipe to the packer, and means within said inner pipe below said passage means for closing off fluid flow downwardly through the

inner pipe while fluid pressure is communicated to the packer.

6. Oil well equipment comprising a pipe string including an inner pipe and an outer pipe spaced therefrom, an expansible packer carried by said outer pipe near the lower end thereof and adapted to be expanded against the well bore, means for expanding said packer, vertically spaced ports in said inner pipe providing communication between said inner and outer pipes, valves controlling fluid flow through said ports, and means for individually and selectively controlling said valves.

7. Oil well equipment as recited in claim 6, including a drilling tool carried by the lower end of said string and spaced beneath said ports and containing passages through which said pipes are in communication with each other and with the well.

8. Oil well equipment as recited in claim 7, in which said packer is adapted for expansion against the bore wall by fluid pressure, and including passage means for communicating fluid pressure from the inner pipe to the packer, means within said inner pipe below said passage means for closing off fluid flow downwardly through the inner pipe while fluid pressure is communicated to the packer, and check valve means for preventing reverse fluid flow through said passage means from the packer to said inner pipe to maintain the packer in inflated condition.

9. In oil well equipment of the type comprising a drill string including spaced inner and outer pipes and in which fluid is circulated downwardly within one of said pipes and then upwardly within the other; the improvement comprising an expansible packer carried by said outer pipe near the lower end thereof and adapted to be expanded by fluid pressure against the well bore wall, passage means for communicating fluid pressure from the inner pipe to the packer, means within said inner pipe below said passage means for closing off fluid flow downwardly through the inner pipe while fluid pressure is communicated to the packer, and valve means for preventing reverse fluid flow through said passage means from the packer to said inner pipe to maintain the packer in inflated condition.

10. A combination as recited in claim 9, including means for opening said valve means to deflate the packer.

11. A combination as recited in claim 9, including a port in said inner pipe providing communication between said inner and outer pipes at a location spaced above said passage means, a valve controlling fluid flow through said port, and means for actuating said valve.

12. The method of displacing a liquid from within a double walled string of well tubing containing two passages, which comprises applying a

gas under pressure to the upper end of one of said passages, and sequentially providing communication between said two passages at vertically spaced locations, whereby the liquid will be progressively displaced from the string passages by the gas.

13. The method as recited in claim 12, in which said gas is applied under pressure to the space between the two walls of said tubing, and forces the liquid upwardly within the inner wall.

14. The method of testing a well comprising lowering into the well a double walled string of well tubing containing two passages one about the other, closing the space between said string and the well bore wall at a location near the lower end of the string, applying a gas under pressure to the upper end of one of said passages, sequentially providing communication between said two passages at vertically spaced locations, whereby well liquid contained in the string passages will be progressively displaced therefrom by said gas, and then testing the well while said space between the string and bore wall remains closed at said location.

15. The method of displacing a liquid from within, and a formation sample upwardly through, a double walled string of well pipe positioned within a well and containing two passages one about the other communicating with each

30 other and with the well through a drilling tool carried at the lower end of the string, that comprises closing the space between the string and the well bore wall near the lower end of the string, applying a compressed gas to the upper end of

35 one of said passages, sequentially providing communication between said two passages at vertically spaced locations above said tool, whereby the liquid will be progressively displaced from the string passages by said gas, and then circulating

40 said gas downwardly through one of said passages and to said tool and then upwardly through the other passage to the surface of the earth to elevate a sample of the earth formation to the surface by said circulation.
